(57) **CLAIM**

The ornamental design for a blister package, as shown and described.

DESCRIPTION

FIG. 1 is a perspective view of a blister package of the present invention;

FIG. 2 is a front view of the blister package of FIG. 1;

FIG. 3 is a back view of the blister package of FIG. 1;

FIG. 4 is a side view of the blister package of FIG. 1;

FIG. 5 is the other side view of the blister package of FIG. 1;

FIG. 6 is a top view of the blister package of FIG. 1; and,

FIG. 7 is a bottom view of the blister package of FIG. 1.

1 Claim, 5 Drawing Sheets
